UNITED STATES PATENT OFFICE.

HENRY C. PEASE, OF WORCESTER, MASSACHUSETTS, ASSIGNOR OF ONE-HALF TO LESTER J. PEASE, OF SAME PLACE.

SOLE-CUTTING MACHINE FOR BOOTS AND SHOES.

SPECIFICATION forming part of Letters Patent No. 276,979, dated May 1, 1883.

Application filed August 5, 1882. (No model.)

To all whom it may concern:

Be it known that I, HENRY C. PEASE, of Worcester, in the county of Worcester and State of Massachusetts, have invented certain new and useful Improvements in Machines for Cutting Soles for Boots and Shoes and other Similar Purposes; and I declare the following to be a description of my said invention, sufficiently full, clear, and exact to enable others skilled in the art to which it appertains to make and use the same, reference being had to the accompanying drawings, which form a part of this specification.

My present invention relates to certain improvements in the construction of that class of machines which are employed for cutting out the soles of boots and shoes or other similar articles by the aid of cutting-dies, the objects of the invention being to provide a more serviceable, convenient, safe, and efficient machine than those heretofore in use; to make the supporting frame so that it shall be strong and rigid against torsional strains or twisting action when the die is used under one end of the striker or follower; to afford a double guide for the follower, so that its plate will operate square and level with the block or cutting-bed; to provide mechanism for intermittently operating the striker without the necessity of an automatic stop-clutch upon the driving-shaft; to provide means for sustaining the striker against accidental depression; to impart greater stability and permanence to the mechanism by locating the heavy moving parts near the base to avoid shocks and severe strains by the stopping and starting of the mechanism when making the stroke or driving the die, and to render the machine operative without waste of power; also, to afford convenient facilities for actuating the block-adjusting mechanism. These objects I attain by the mechanism constructed in the manner herein illustrated and described, the particular subject-matter claimed being hereinafter definitely specified.

In the drawings, Figure 1 represents a top view of a sole-cutting machine embracing my invention. Fig. 2 is a vertical longitudinal section at line *xx*. Fig. 3 is a front view of the machine. Fig. 4 is a sectional plan view at line *yy*. Fig. 5 is a transverse vertical sec-

tion through the striker-head. Fig. 6 is a transverse section of the top frame and working-lever, and Fig. 7 is a view of the handle for actuating the block-adjusting devices. 55

In referring to the drawings, A denotes the main frame; B, the block or cutting-bed; C, the operating crank-shaft; D, the depressing-lever; E, the crank-connector or pitman; F, the follower or striker; G, the starting-treadle; H, the treadle rods or connections; I, the quoin-block or chocking-piece; K, the head-balance or elevating-spring; L, the adjusting-handle for working the block-elevating gears, all of which parts are located in relation to 60 each other as indicated.

The frame A, I construct in the peculiar form shown, with two vertically-extending ribs or webs, A', located at some distance apart upon the body-flange *a*, and running parallel, or nearly so, from the lower front of the machine around the back and to the upper front of the overhanging portion or head, said webs A' being connected or braced to each other and to the body-flange *a* at occasional intervals by 65 transverse webs or ribs *a'*, the whole being cast integral or in a single piece. Said frame is mounted upon legs or standards A², that are bolted to suitable lugs or laterally-projecting ledges formed at the sides of the frame, as indicated. Bearings *c* and *d* are formed on the two webs A' to support the journals of the operating crank-shaft and driver-lever, and at the upper front end are two vertical bearings or guideways, *f*, for supporting the striker-head 70 75 F. The peculiar construction of this frame with the two webs A' is a feature of my invention, the purpose of which is to prevent the twisting springing of the frame by torsional strain occasioned when using the die 80 85 90 under the extreme end of the striker-plate.

The block or cutting-bed B is made of wood in ordinary form, and rests upon a flanged metal plate, B', supported by four screws, *b*, that pass down through the main frame A, 95 and are provided with geared nuts *m*, as indicated. Said screws are held tightly at their upper ends in the plate B'. The gear-nuts *m* severally mesh with the central gear, M, and the height of the block is adjusted in the usual 100 manner by revolving the gear M and nuts *m*.

For revolving the gear M, I employ a han-

idle-lever, L, which is pivoted on the central stud of the gear M and projects at the front of the machine. Upon this handle is arranged a latch-lever, l, (see Figs. 4 and 7,) having a depending point that passes through the handle-lever and engages with the teeth of the gear M for moving the gear when the handle is carried to the right or left. By pressing down the latch-lever l its point is released from the gear-teeth, so that the handle can be shifted for taking a new hold. By this means the gear can be moved as required, either to the right or left, in a very convenient and easy manner.

The shaft C is mounted in bearings c at the lower rear part of the frame A, with its crank between the webs A'. At one end it is furnished with tight and loose pulleys C' and at the opposite end with a large fly-wheel, C².

The working-lever D is arranged between the webs A' and is fulcrumed on the upper part of the frame at d, with its forward end over the striker F and between the guides, while its rear end curves downward at the rear of the machine and is linked to the crank-shaft C by the pitman or connecting-piece E, as illustrated. The forward end of the lever D is made with a suitable face or offset, i, to engage the chock-piece or quoin I for forcing down the striker F, and with a suitably-rounded surface at the top for raising said striker.

The construction, location, and arrangement of the driving-shaft and striker-lever mechanism are features of my invention, the purposes of which are to give greater stability and less vibration by bringing the heavy moving parts nearer the base of the machine to give greater length of leverage; to continuously move the lever when the machine is in operation, and thus, by reducing the number of parts that require to be stopped and started at each blow, avoid loss of power and excessive straining on the driving parts; also, to obviate the necessity of an automatic clutch mechanism on the shaft—a device which rapidly wears out and is liable to frequent derangement.

The striker F is made with two guiding-standards, F', which work in the vertical guideways f on the head of the frame. Between these two guides is arranged a steel shoe, F², having a semi-cylindrical cavity, which forms a seat for the heel of the swinging chock-piece or quoin I, which latter is pivoted between suitable ears extending upward from the sides of the shoe F², as illustrated. The chock-piece and shoe are fitted to each other with a close-working joint. The shoe is secured firmly to the striker-plate, and the top of the chock-piece is properly squared and fitted to swing under and receive the end or face i of the depressing-lever D, whereby the striker is forced down for giving the blow upon the die for cutting the leather. The guides F', which are preferably of cylindrical form, are joined at their upper ends by a bar or yoke, F³, the ends of the pieces F' being firmly fitted to the yoke and plate F by counterbored and shouldered seatings. The parts are connected

by strong bolts, F⁴, which extend through the interior of the cylinders F' from the bottom to the top (see Fig. 5) and clamp the parts securely together, so as to give a square rigid head-piece, with the guides F' parallel to each other. By employing the guides F' with the depressing devices arranged intermediate or between them the striker is caused to work straight and level, and is prevented from canting or taking an inclined position and cramping on the joints when the die is set under one end of the plate.

The balance-spring K consists of a series of flat leaves or plates seated upon and attached to the frame A in the manner illustrated. The end of the longer leaf is extended through an opening in the yoke or bar F³, or otherwise suitably attached for elevating the striker. The tension of the spring K is made sufficient to balance or retain the striker in elevated position, so that there is no liability of the striker descending accidentally and injuring the operator while placing the die, as sometimes occurs with machines of other construction.

The quoin I is swung to and from the depressing-lever by the starting-treadle G, to which it is connected by the rods H H, one of which is pivoted to the side of the quoin and extends from these to an angle-lever, H', pivoted to the rear of the frame, while the other extends from said angle-lever to the rear end of the treadle G, as shown in Fig. 2. Depression of the treadle G swings the top end of the quoin I beneath the end of the working-lever D, so that the face i engages the end of the quoin and the striker F is depressed thereby. When the treadle is released it is raised by its spring G', and the quoin I is swung outward or away from the end of the lever D, so that the lever passes it without actuating the striker.

The construction of the striker with two guides, the balancing-spring, and the manner of operating the head by means of the swinging quoin or chock-piece in connection with the working-lever, are features of my invention.

I am aware that leather-cutting machines have heretofore been made wherein a vertically-moving striker is intermittently actuated by lever mechanism; but in such machines the construction and action of the devices are different from the improvements herein described.

What I claim as of my invention, and desire to secure by Letters Patent, is—

1. In a sole-cutting machine, the frame A, having two vertical webs, A', arranged in relation to each other and the body-flange a, and provided with transverse ribs a', all of a single casting, substantially as shown and for the purpose stated.

2. The combination, with the frame A, provided with two vertical webs, A', terminating at the head in guideways or bearings f, of the striker F, provided with two guiding-cylinders, F', and an intermediately-located operating

mechanism for depressing said striker, substantially as set forth.

3. The striker for leather-cutting machines, constructed of the plate F, guide-cylinders F', top yoke, F³, connecting-bolts F⁴, and pressure-shoe F², arranged substantially as shown and described.

4. The combination, substantially as described, of the double-webbed frame A, of the crank-shaft C, its pulleys C' and fly-wheel C² mounted or supported by bearings c, located at the lower part of said frame, and the working-lever D, fulcrumed at d on the top part of said frame, with its rear end curved downward between the webs A' at the back of the frame, and linked to the shaft-crank by pitman-piece E, as illustrated, and for the purpose set forth.

5. The combination, substantially as described, of the striker F, having double guides, F', the depressing-lever D, fulcrumed on the frame, as shown, with its end vibrating between the guides above said striker, the chock-piece or quoин I, adapted for movement from

or beneath said lever, and means for operating said parts, as hereinbefore set forth.

6. The combination of the striker F, the vibrating lever D, the movable quoин or chock-piece I, the treadle G, and connections H H', the pitman E, and the crank-shaft C, having swing-pulleys C' and fly-wheel C², substantially as and for the purpose set forth.

7. In a sole-cutting machine, the spring K, in combination with the striker F and the depressing mechanism, substantially as and for the purpose set forth.

8. The combination, with the block-supporting plate B', its adjusting-screws b, nuts m, and actuating-gear M, of a hand-lever, L, provided with a latch device for engaging and moving said gear, substantially as set forth.

Witness my hand this 12th day of July, A. D. 1882.

HENRY C. PEASE.
